CLAIM

The ornamental design for a container with cap, as
 shown and described.

DESCRIPTION

FIG. 1 is a perspective view of a container with cap
 showing my new design;

FIG. 2 is a left side elevational view thereof; the right

side elevational view being a mirror image thereof;

FIG. 3 is a bottom plan view thereof; and,

FIG. 4 is a rear elevational view thereof.

Fig. 1.

Fig. 2.

Fig. 4.

Fig. 3.
